UNITED STATES PATENT OFFICE.

JOHANNA JAMES STRAIN, OF CHRISTCHURCH, NEW ZEALAND.

HOT-WATER-SERVICE ATTACHMENT TO THE BURNERS OF GAS HEATER STOVES OR TO THE GAS-RINGS USED FOR HEATING POTS, IRONS, &c.

No. 902,119.

Specification of Letters Patent.

Patented Oct. 27, 1908.

Application filed April 29, 1907. Serial No. 370,756.

To all whom it may concern:

Be it known that I, JOHANNA JAMES STRAIN, married woman, subject of the King of Great Britain, residing at Christchurch, in the Colony of New Zealand, have invented a new and useful Improved Hot-Water-Service Attachment to the Burners of Gas-Heated Stoves or to the Gas-Rings Used for Heating Pots, Irons, or the Like; and I do hereby declare the following to be a full, clear, and exact description of the same.

My invention relates to improvements in the burners of gas heated stoves or to the gas rings for heating pots, irons or the like, in which means are provided whereby the heat given off from the burners may be utilized for boiling water at the same time as being used for other purposes.

Various hot water service attachments for gas heated stoves and the like have been used hitherto, and my present invention has reference to that type of hot water service attachment in which a ring or pipe is suitably connected to a water tank and is adapted to be heated by the gas ring or the like when in use.

In order that my invention may be more readily understood I will refer to the accompanying drawings in which:—

Figure 1 shows a side elevation of my invention applied to a gas ring; Fig. 2 shows a plan of Fig. 1, and Fig. 3 is a large sectional view of the gas ring surrounding the water ring.

In applying my invention to a burner of a gas-heated stove I construct two pipes, one within the other, the inner pipe adapted to contain water. The gas pipe will thus surround the inner circle or pipe, and the outer pipe will be provided with the usual jets or openings in the ordinary manner. The wa-

ter pipe will be supplied with water from a suitable tank or reservoir placed in any convenient place, and will be connected thereto by inlet pipes. Since hot water rises, the outlet pipe will be carried to a higher level in the reservoir than that from which the inflow pipe leads, and a circulation of water will thus be obtained.

a is an ordinary gas ring and *b* is the water pipe, constructed with a loop at its middle portion, which loop is concentric with and is inclosed in the gas ring *a* in the manner shown in Fig. 3, the two ends of the water pipe being adapted to pass into a tank *e*. This tank *e* is preferably constructed so that it can be easily carried about from one place to another. It may be provided with a tap *f*. One end of the water pipe *b* extends to a high level in the tank and is used for carrying the hot water to a higher level therein than the receiving end of the pipe, in order to keep up a constant circulation of the water in the branches of the pipe and through the loop. Thus tube *b* will be heated and the water therein will circulate to the higher end of the tube, said end opening into the water tank, and thereby heat, which would otherwise be wasted, is put to a useful purpose.

What I claim is:

In combination, a water tank, a gas ring and a water pipe having a loop inclosed within and concentric of said gas ring, the ends of the water pipe aforesaid opening to the interior of said tank.

In testimony whereof, I have signed this specification in the presence of two subscribing witnesses.

JOHANNA JAMES STRAIN.
